UNITED STATES PATENT OFFICE.

WILLIAM MILLS, OF NEW ATHENS, OHIO.

IMPROVEMENT IN APPARATUS FOR CLEANSING FEATHERS.

Specification forming part of Letters Patent No. 33,594, dated October 29, 1861.

To all whom it may concern:

Be it known that I, WILLIAM MILLS, of New Athens, in the county of Harrison and State of Ohio, have invented a new and Improved Feather-Renovator; and I do hereby declare that the following is a full, clear, and exact description of the same, reference being had to the annexed drawings, making a part of this specification, in which—

Figure 1 is a side sectional view of my invention, taken in the line $x x$ of Fig. 2; and Fig. 2, a transverse vertical section of the same, taken in the line $y y$ of Fig. 1.

Similar letters of reference indicate corresponding parts in the two figures.

The object of this invention is to obtain a feather-renovator which will be extremely simple in construction, very portable, so that it can readily pass through a door of ordinary dimensions and still be capable of operating in a very efficient manner.

The invention consists in the employment or use of an ellipsoidal steam-chest or drier placed centrally within a corresponding-shaped feather-receptacle, which is suspended on an axis and provided with steam-pipes, the above parts being used in connection with a blast or discharging fan, all arranged to effect the desired end.

To enable those skilled in the art to fully understand and construct my invention, I will proceed to describe it.

A represents a stand or framing, which may be constructed in any proper way to support an ellipsoidal feather-receptacle B, the axis C of which is fitted in proper bearings $a a$ on the framing, the axis and feather-receptacle being somewhat inclined, as shown in Fig. 1.

Within the feather-receptacle B there is fitted or placed centrally an ellipsoidal steam-chest D, which is considerably smaller than the feather-receptacle B, as will be seen by referring to Fig. 2. The axis C of the feather-receptacle B (which axis is a tube) passes centrally through the steam-chest D and communicates at one end with a steam-pipe E from a steam-boiler, and F F are two branch tubes, which pass through the feather-receptacle B at opposite sides of the steam-chest D, the pipes F being perforated, as shown at b, and communicating with the steam-pipe E, each tube C F F being provided with a cock

c for the purpose of cutting off steam, when necessary.

G is a blast-fan which is placed within a suitable case H, provided with a spout I. This spout, when the fan G is in use, is inserted in one end of the feather-receptacle B in the plane of its major diameter, and a discharge-opening J is made in the opposite end of the feather-receptacle at a corresponding point. The feather-receptacle B is provided with a door K, through which the receptacle is supplied with feathers.

The operation is as follows: The receptacle B is supplied with the feathers which are to be renovated, and steam is admitted into the tubes C F F while the receptacle B is turned. The tube C heats the chest D, from which heat is radiated into the receptacle B, and consequently into the midst of the feathers. The feathers are renovated or cleansed by the admission of steam through the pipes F F, the heat from D drying the feathers when cleansed, and after the steam is cut off from the tubes F F the vapor passing through a perforated cover G in the receptacle B, the close cover G' being removed to admit of such result. When the feathers are thoroughly dried, the end of the blast-spout I is inserted in the end of the feather-receptacle B, the latter being stationary and so adjusted that its major diameter will be in a vertical position. By this means it will be seen that the dried and renovated feathers are brought within a narrow space—to wit, the lower part of the receptacle B—and by rotating the fan G with a proper speed the feathers will all be discharged from the receptacle.

The ellipsoidal form of the feather-receptacle effects two important results, to wit: first, the ready expulsion of the feathers through the medium of the fan, owing to the former settling down into a narrow passage in line with the blast, and, second, the enabling of the device to be carried through a door of ordinary dimensions by simply turning the feather-receptacle B so that its major diameter will be in a vertical position. By having the steam-chest D at the center of the receptacle B the feathers will be heated and dried by a moderate expenditure of steam, as the heat from chest D is radiated directly among the feathers, the chest D not being at

all exposed to the external air. The steam-tubes F F also perform two functions, to wit: first, the admission of steam into the receptacle B for the purpose of renovating the feathers, and, second, the scattering or spreading of the feathers during the rotation of the receptacle, so that the feathers may be fully acted upon and cleansed.

I do not claim the renovating of feathers by means of steam passing into a rotating receptacle irrespective of the construction and arrangement herein shown and described, for such device has been used for the purpose; but

What I claim as new, and desire to secure by Letters Patent, is—

1. The employment or use of an ellipsoidal feather-receptacle B and steam-chest D, arranged as and for the purpose set forth.

2. In combination with the ellipsoidal feather-receptacle B and steam-chest D, the perforated steam-tubes F F C, and blast-fan G, all arranged for joint operation, substantially as and for the purpose set forth.

WILLIAM MILLS.
